ABSTRACT: A side arm firm arm support comprising a stiff flat member having a loop to snugly embrace a belt, and an upstanding back portion of a length to over reach the upper edge of the trouser's waistband, an inwardly extending portion adapted to extend over the waistband edge and of a length to support the trigger guard of a firearm, and an upwardly extending lip on the inner end of the inwardly extending portion to engage behind the trigger guard.

PATENTED DEC 29 1970

3,550,821

INVENTOR.
ANDREW G. DAIGLE

BY J. O. Kepner

ATTORNEY

SIDE ARM BELT SUPPORT

This invention relates to a belt supported small arms carrier.

The carrying of side arms by enforcement officers and the like has usually required a holster either supported from the hips or shoulder. Such holsters are unduly heavy, uncomfortable, burdensome and difficult to conceal. The present invention is directed to a support adapted to be threaded upon the usual belt passing through the belt loops in the waistband of trousers, and is adapted to support a pistol with its nose or barrel inside the pants waistband, the support having an upstanding inwardly extending portion adapted to engage the trigger guard of the firearm. The support is light in weight, effective in supporting the firearm in a safe but instantly accessible manner, and without the discomfort of holsters and the like.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

FIG. 1 is an elevational view of the support shown with a side arm supported thereby and positioned on the belt around the waistline of trousers, fragmentarily shown;

FIG. 2 is a sectional view through the waistband taken substantially on the line 2-2 of FIG. 1;

FIG. 3 is a fragmentary perspective view of the support applied to a waistline belt, and

FIG. 4 is a side elevation of the support.

Referring to FIG. 1 there is shown a waistline belt 20 threaded through suitably spaced belt loops 22 and 24 of a waist construction 26 of a pair of trousers. The section of the belt indicated is that to the left of the wearer and forward of the left hip, and the other belt end 21 extending from the belt buckle, not shown, as indicated.

Threaded on the belt is a support member 30 having a loop portion 32 adapted to be threaded on the belt 20. The member may be formed of hard brass strip about seven-sixteenths inches wide and about one-sixteenth inch thick. As shown the member is provided with an upstanding back portion 34, having a lower 180°bend at 36 to form the loop 32, which may be closed by the inwardly bent upper end 37.

The back portion 34 extends above the bent upper end 37 by a distance about equal to the height of the upper edge 38 of the waistband construction 26, and is provided with an integral inwardly projecting portion 40 to support the trigger

guard 41 of a side arm 42 behind the trigger 44 in the manner about as indicated in FIG. 1. A short upwardly extending lip 46 is provided to engage the inside edge 48 of the rear of the trigger guard about as indicated in FIG. 2. The lip 46 holds the side arm from sliding inwardly off the portion 40, and as shown, the side arm when supported with barrel inside the waistband, will assume a balanced position about as indicated, which lies at an angle that will nest in or be above the angular line between the wearer's upper left thigh and lower torso.

10 It will be seen that the side arm as thus carried is instantly accessible for removal by grasping the grip 60 with the right hand, the lip 46 being quickly cleared by the space between the rear of the trigger guard and the trigger 44. With the support, almost no additional weight is added, the fire arm is 15 securely supported in place, and is readily accessible or replaceable with safety. The wear's garments, are protected from wear, since the bulk of the firearm is inside of the waistband and cannot contact the jacket, or the exterior of the trousers.

20 While dimensions and material such as brass have been referred to, other materials and dimensions to suit varying belts and side arms can be employed. The use of brass presents a relatively soft material to the trigger guard ring so as to avoid abrasive or cutting action thereto. While the illustration and 25 reference has been for use by right-handed individuals it will appear that the support may be located so as to serve left-handed persons with equal ease. In fact, whether located to the left or to the right, the weapon is readily accessible to either hand.

30 While a single form of the invention has been illustrated and described, it is to be understood that the invention is not limited thereto. As various changes in the construction and arrangement may be made without departing from the spirit of the invention, as will be apparent to those skilled in the art, 35 reference will be had to the appended claims for a definition of the limits of the invention.

I claim:

1. A side arm fire arm support comprising a stiff flat member having a back portion adapted to be positioned between the belt and waistband of the trousers of an enforcement officer or the like, the back portion having a loop to snugly embrace a belt, and an upstanding upper portion of a length to over reach the upper edge of the waistband, an inwardly extending portion adapted to extend over the 45 waistband edge and of a length to support the trigger guard of a firearm, and an upwardly extending lip on the inner end of the inwardly extending portion to engage behind the trigger guard, said lip being of a height less than the spacing between the trigger guard and the rear of the trigger of the firearm to 50 which it is adapted.
